W. J. LARSON.

PISTON COOLING DEVICE FOR INTERNAL COMBUSTION ENGINES.
APPLICATION FILED JUNE 30, 1919.

1,346,407.

Patented July 13, 1920.

UNITED STATES PATENT OFFICE.

WALTER J. LARSON, OF WRANGELL, TERRITORY OF ALASKA.

PISTON-COOLING DEVICE FOR INTERNAL-COMBUSTION ENGINES.

1,346,407.

Specification of Letters Patent. Patented July 13, 1920.

Application filed June 30, 1919. Serial No. 307,498.

To all whom it may concern:

Be it known that I, WALTER J. LARSON, a citizen of the United States, and resident of Wrangell, Territory of Alaska, have invented certain new and useful Improvements in Piston-Cooling Devices for Internal-Combustion Engines, of which the following is a specification.

My invention comprises an improvement in water-cooled pistons, and in means for connecting such pistons with a supply of cooling water. While I describe my invention as using water for cooling purposes, any suitable fluid may be used. My invention may also be used in connection with many types of engines, and it is not my intention to limit its application to any particular type.

The object of my invention is to provide a simple means of cooling a piston of an engine, in order to prevent excessive heat therein. Such excessive heat may cause cracking or binding.

Another object is to provide a piston-cooling device of few parts, and one which will eliminate excessive vibration and leakage.

My invention comprises the novel parts and combinations of parts shown in the accompanying drawing, described in the specification, and defined by the claims terminating the same.

In the accompanying drawing I have shown my device in a form now preferred by me. It is obvious that this may be altered in design and construction without departing from the principles of my invention.

The drawing illustrates an internal combustion engine with my device installed, in section.

Types of cooling devices for pistons which employ oscillating arms have been found to vibrate and to bind in practice, this causing an excessive leakage of the cooling fluid and rapid breakdown of the cooling system. In order to obviate this difficulty my present device contains only reciprocating members, all aligned. The packings employed are all of a type which permit very little, if any, leakage, and which will not bind or loosen with use.

Reciprocable in a cylinder casing 1, which may be of any suitable type, is a piston 2, connected with the crank 20 by a connecting rod 21. The piston 2 may be of any suitable type, except that it has a hollowed head 23 extending beneath the inner surface.

Extending upward into the hollowed head 23 is an inlet pipe 3 and a discharge pipe 4. As here shown, the upper end of the discharge pipe 4 is somewhat higher than the end of the inlet pipe 3. The object of this is never to permit the level of the water in the head 23 to fall below the level of the end of the pipe 4, thus keeping some water in the head at all times. These pipes 3 and 4 are fixedly secured in the piston 2 at 30 and 40 respectively, and may also be secured in lugs 24, near the lower end of the piston.

Fixedly secured to the casing 1 are standpipes 5 and 6. The inlet standpipe has an inlet connection with a source of cold water at 50, and the discharge standpipe 6 has a water discharge connection at 60. I have illustrated these standpipes as bent at one end, and fixedly secured by their ends at 75 11 and 12 to the casing 1. These standpipes 5 and 6 are straight between the securing points 11 and 12, and their axes are alined with the axis of the cylinder 1.

Surrounding the inlet and discharge standpipes 5 and 6 are inlet and discharge tubes 7 and 8, respectively. These tubes are closed at both ends, and are adapted to reciprocate upon the standpipes 5 and 6. Any suitable packing box may be used, as shown at 70 and 80. Ports 52 and 62 provide channels for the water between the interior of the tubes 7 and 8 and the standpipes 5 and 6, respectively, at all times and in all positions of the tubes upon the standpipes.

The tubes 7 and 8 are rigidly connected with the piston 2, to move therewith. In the present preferred form of construction this rigid connection takes the form of connecting pipes 71 and 81, which are secured in the tubes 7 and 8, and to the lower ends of inlet pipe 3 and discharge pipe 4, respectively. The connecting pipes 71 and 81 pass through slots 13 in the casing 1, and complete the water circuit through the head 23 of the piston 2.

When the piston 2 reciprocates in the cylinder 1, the inlet tube 7, being connected rigidly thereto by means of the inlet pipe 3 and connecting pipe 71, reciprocates with the piston, and at the same rate, upon the standpipe 5. In the same way the discharge tube 8 reciprocates upon the discharge standpipe 6. All parts being rigidly fastened to either the piston 2 or the casing 1, and reciprocating parts being alined, no oscillatory

motion takes place, and vibration is thereby materially reduced. Any suitable means may be used to force water through the circuit, entering at 50.

5. What I claim as my invention is:
  1. In combination, a cylinder casing, a hollow piston reciprocable therein, fluid inlet and discharge pipes fixedly secured in said piston to be reciprocable therewith, and 25 adapted to permit a flow of liquid through the piston, inlet and discharge standpipes alined with the axis of said cylinder, and fixedly secured to said casing, an inlet tube and a discharge tube each closed at both ends and 30 surrounding the inlet and discharge standpipes, respectively, and reciprocable thereon, fluid passages connecting said standpipes with the interior of said tubes, and means connecting the inlet and discharge pipes 35 with the inlet and discharge tubes, respectively.

2. In combination, a cylinder casing, a hollow piston reciprocable therein, fluid inlet and discharge pipes fixedly secured in said piston to be reciprocable therewith, and 25 adapted to permit a flow of liquid through the piston, inlet and discharge standpipes alined with the axis of said cylinder, and offset laterally from the inlet and discharge pipes, said standpipes being fixedly secured 30 to said casing, an inlet tube and a discharge tube each closed at both ends and surrounding the inlet and discharge standpipes, said standpipes having fluid ports opening into the interior of said tubes at all times, and 35 means rigidly connecting the inlet and discharge pipes with the inlet and discharge tubes, respectively, and forming a fluid conduit therebetween.

Signed at Wrangell, Alaska, this 17th day 40 of June, 1919.

WALTER J. LARSON.
